UNITED STATES PATENT OFFICE.

HARVEY S. PARDEE, JOHN A. DEWIRE, AND JAMES W. SUPORTER, OF CHICAGO, ILLINOIS, ASSIGNORS TO MILLER AND PARDEE, INC., OF CHICAGO, ILLINOIS, A CORPORATION OF ILLINOIS.

DESIGN FOR A RADIATOR CAP.

60,878.

Specification for Design.

Patented Apr. 18, 1922.

Application filed July 9, 1921. Serial No. 483,576. Term of patent 14 years.

To all whom it may concern:

Be it known that we, HARVEY S. PARDEE, JOHN A. DEWIRE, and JAMES W. SUPORTER, all citizens of the United States, all residing in Chicago, Cook County, Illinois, have invented a new, original, and ornamental Design for Radiator Caps, of which the following is a specification, reference being had to the accompanying drawing, forming part hereof.

Fig. 1 is a front elevation of the radiator cap.

Fig. 2 is a left side elevation thereof.

We claim:

The ornamental design for a radiator cap, substantially as shown.

In testimony whereof: we have signed our names to this specification this 2d day of July, 1921.

HARVEY S. PARDEE.
JOHN A. DEWIRE.
JAMES W. SUPORTER.
